UNITED STATES PATENT OFFICE.

JOHN THOMAS DANIELS, OF NEWARK, NEW JERSEY, ASSIGNOR TO THE HANSON & VAN WINKLE CO., OF NEWARK, NEW JERSEY, A CORPORATION OF NEW JERSEY.

PHONOGRAPH-RECORD MATRIX AND METHOD AND APPARATUS FOR PRODUCING SAME.

Application filed September 30, 1919. Serial No. 327,471.

To all whom it may concern:

Be it known that I, JOHN T. DANIELS, a citizen of the United States, residing at Newark, county of Essex, State of New Jersey, have invented a certain new and useful Improvement in Phonograph-Record Matrices and Methods and Apparatus for Producing Same.

My invention relates in general to the production of disc records for phonographs and more particularly to the matrix from which the records are made.

In the usual process of making these records, an impression of the sound vibrations is taken in wax or other pliable material, after which the soft record is made electrically conductive on this surface and the hard material deposited thereon. The deposited material is then stripped from the original soft record and may for example be used directly for the impression of the multiple copies in a suitable composition disc for sale. My invention provides an improvement in this general process. The matrix above referred to when produced according to the usual electroplating process does not lie perfectly flat but has produced upon it, by the electrolytic action, a series of circular waves or undulations concentric with the center of the matrix. Apparently from this cause, uneven tensions are set up in the thin metallic structure and the matrix tends to buckle. Furthermore the uneven thickness, over different portions of the matrix, renders it impractical to take even impressions from it, as unequal pressures are transmitted by the different thicknesses.

According to my invention the matrix is apparently of equal tension throughout and has no tendency to buckle when stripped from the soft impression on which it is deposited. It rests perfectly flat, and is of constantly uniform thickness throughout, with the exception of the extreme periphery which is readily trimmed off or otherwise manipulated to obtain the uniform thickness to the very edge. I accomplish this result by what I believe to be a new method of electroplating and by the use of apparatus which constitutes an improvement over the prior art. An important feature of the method and apparatus is to be found in the

peculiar movement given to the cathode during the deposition of the matrix thereon. The invention will be clearly understood from the description of one or two embodiments thereof, illustrated in the accompanying drawings.

In said drawing:

Figure 1 is a diagrammatic view partly in vertical section of one form of apparatus which may be employed.

Figure 2 is a plan view thereof.

Figure 3 is a vertical section taken parallel to the plane of the matrix showing the construction of operating member by which the desired movement of the cathode may be secured.

Figure 4 is a vertical section of the same, taken transversely of the plane of the matrix, with parts in full elevation.

Figure 5 is a detail top plan view showing a pawl and ratchet mechanism employed on the operating member.

Figure 6 is a diagrammatic view, in elevation, of another form of apparatus for obtaining substantially the same results.

Referring to said drawing, 10 indicates diagrammatically a vat or tank containing the bath 11 of any suitable electroplating composition, for example the nickel bath set forth in U. S. Patent 1,352,328 to Todd and King and obtainable in the market under the name "Capitol". The anodes 12 of nickel may be hung from the anode bars 85 or rods 13 at two sides of the tank, with suitable space between the two groups of anodes to accommodate the cathode between them. In the example shown, the cathode is in the form of two discs 14 (Figs. 1 and 2) which are hung from an operating member, the construction of which will be better understood from Figures 3, 4 and 5 of the drawing. Referring to these figures the operating member is shown as comprising two elongated bars or strips 15, of insulating material, which are suitably recessed to have mounted within or between them the conducting bar or strip 16, the lower end of which is bifurcated or provided with a fork 17 within which is mounted a worm gear 18, whose shaft 19 projects from the opposite faces of the operating member 15 and serves as a conducting and rotating sup-

port for the cathodes 14. The upper end of the conducting bar 17 may have a transverse conducting pin or trunnion 20 projecting through the two faces of the operating member 15 and adapted to rest in slots or notches 21 formed in the bifurcated end of an operating lever 22, (Fig. 1) which in the example shown is fulcrumed in the bracket 23, and oscillated by an eccentric mechanism 24, whose pin 25 rides in the slotted outer end 26 of the operating lever 22. Electrical connection may be made with the pin 20 by means of conductor 28, so that the current from the cathodes 14 passes thru shaft 19, worm gear 18, fork 17, bar 16, and trunnion 20 from which the conductor 28 leads back to the source.

The operating member 15 is also provided with the rotary longitudinal shaft 29, which has a worm 30, secured on its lower end, in mesh with the worm gear 18. The upper end of shaft 29 projects beyond the top of operating member 15 and has fixed thereon a ratchet wheel 31 with which a pawl 32, mounted adjacent thereto on the top of operating member 15 is resiliently held in engagement by means of its leaf spring 33. The operating lever 22 is provided near its free end with a bracket 34 on which is mounted a pawl 35, normally held in position by springs 36 to engage with the teeth of ratchet wheel 31. During the oscillation of operating lever 22 the operating member 15 assumes a pendulum motion upon its trunnion 20 which causes the ratchet wheel 31 to swing past the operating pawl 35 so that the shaft 29 is turned a slight distance with each swing of the pendulum.

The entire operation will now be apparent. Eccentric mechanism 24 is set in motion, the current is permitted to flow from anode bars 13, and anodes 12 thru the solution 11 and cathodes 14 and so forth, as already described. As the eccentric mechanism rotates, the operating lever 22 swings up and down, causing movement of the trunnions 21 upon an arc whose center is in the fulcrum or axis of the lever 22. This motion not only causes the cathodes to rise and fall, but by reason of the angular motion imparted to the trunnions 21, a transverse or pendulum swing is also taken on by the cathodes, as indicated by the dotted circle in Figure 1. In addition to this more or less circular motion of the cathode axis, the cathode is at the same time given a step by step movement about its axis 19, due to the rotation of the shaft 29, at each engagement of pawl 35 with the ratchet wheel 31. The movement of the cathodes is thus in the nature of a planetary motion, their axis in general describing a circular movement while the discs themselves turn about their axis. The resulting effect of this is to permit the deposition of metal to occur in a uniform and ap-

parently homogeneous structure, with the grain distributed uniformly and evenly in all directions within the plane of the deposits. It builds up evenly over substantially the entire surface and shows no undulations or waves which might cause unequal stresses and result in a structure tending to buckle when stripped off. The deposit may perhaps be regarded as laminated in microscopic layers, with the grain on each layer extending at an angle to that of the next layer due to the fraction of a turn given the disc at each actuation of the ratchet wheel 31.

In practice the first deposition may advantageously be nickel and after a firmly coherent layer of nickel has been built up, a backing of for example copper may be deposited thereon. After suitable thickness is secured, the matrix is then stripped from the wax support, when of course a negative record of the sound waves will be found in the face which was in contact with the wax. The operating member is readily removable from its operating lever, hence it may be conveniently transferred from a nickel bath to a copper bath.

I have shown in Figure 6 of the drawing a diagrammatic view of another mechanism for obtaining substantially the same result. Here it will be understood that the tank 40 is filled with solution as before and the electric circuits similarly arranged, and the only difference being in the mechanism imparting the planetary motion of the cathode. In this instance an operating disc 41 has the operating member 42 swing from an eccentric pin 43 which thus describes a circular movement and while causing the cathode to rise and fall as well as move from side to side in the solution, this movement brings the ratchet wheel 44 into engagement with the fixed pawl 45, so that with each rotation of the disc 41, the ratchet wheel is turned one step and the cathode discs are caused to turn a corresponding distance about their axis as before.

The constructions above described are only by way of example as it will be apparent to those skilled in the art that the desired movements of the cathode can be secured in a great many different ways.

I claim:

1. An electro-deposited matrix for phonographic disk records, the material of said matrix being of substantially uniform tension in all directions when the matrix surface is all in one plane, thereby avoiding a tendency to buckle.

2. A matrix of the character described, comprising a substantially flat disc, having successive layers of nickel and copper, electrolytically deposited and free from uneven tension.

3. The method of producing matrices for

phonographic disc records, which comprises depositing the same from an electrolytic bath upon a suitably constituted cathode, while imparting a substantially planetary motion to the cathode.

4. The method of producing matrices for phonographic disc records which comprises bodily moving the submerged cathode relatively to the anode, while simultaneously 10 turning the cathode upon its axis.

5. Apparatus of the character described comprising in combination suitably disposed anode material, a cathode, suitable electrical connections, and means for imparting to said 15 cathode combined bodily and rotary movement relatively to said anode material.

6. Apparatus of the character described comprising in combination electrically connected anode and cathode materials, and 20 means for imparting planetary motion to said cathode material.

7. The method of treating articles which comprises passing the articles through an

electroplating bath and rotating the articles while in transit through the bath to agitate 25 the bath material.

8. The method of treating articles which comprises passing the articles through an electroplating bath and imparting reciprocatory and rotary movement to the articles 30 while in transit through the bath to thereby agitate the bath material.

9. A process for the production of metal sheets, wire, tubes, cylinders and other articles wherein the cathode has imparted 35 to it an oscillating or reciprocating motion in the electrolyte, substantially as described.

10. A process for the production of metal sheets, wire, tubes, cylinders and other articles wherein the cathode has imparted to 40 it an oscillating or reciprocating motion and also a continuous or intermittent rotary motion, in the electrolyte, substantially as described.

JOHN THOMAS DANIELS.
